CLAIM

The ornamental design for a removable boat moving wheel, as shown and described.

DESCRIPTION

FIG. 1 is a rear perspective view of a removable boat moving wheel showing our new design; the broken lines are for illustrative purposes only and form no part of the claimed design;

FIG. 2 is an enlarged right side elevation view thereof;

FIG. 3 is an enlarged bottom plan view thereof;

FIG. 4 is an enlarged left side elevation view thereof;

FIG. 5 is an enlarged rear elevation view thereof;

FIG. 6 is an enlarged top plan view thereof; and

FIG. 7 is an enlarged front elevational view thereof.

FIG. 1
